UNITED STATES PATENT OFFICE.

DANIEL HEPP, OF CHICAGO, ILLINOIS.

PEN-HOLDER.

SPECIFICATION forming part of Letters Patent No. 243,255, dated June 21, 1881.

Application filed April 22, 1881. (No model.)

To all whom it may concern:

Be it known that I, DANIEL HEPP, of Chicago, in the county of Cook and State of Illinois, have invented a new and Improved Pen-
Holder, of which the following is a specifica-
tion.

The object of this invention is to enable sev-
eral parallel lines to be drawn at one stroke of
the pen. It consists in connecting two pen-
holders to one staff, and securing them together
by set-screws, so that they can be easily and
quickly adjusted to enable the pens to draw
several parallel lines.

In the accompanying drawings, Figure 1
represents the arrangement of the holders on
the staff with the pens in position. Figs. 2
and 3 are views of the tubes connecting the
two holders together.

Similar letters of reference indicate corre-
sponding parts.

Referring to the drawings, A is the staff of
the pen, carrying an ordinary metal holder, B.
B' is a second pen-holder, of the same kind
precisely as B.

C C are two tubes placed together side by
side and soldered. Their connection is further
strengthened by a band, a, passed around
them, binding them together. Set-screws b b
are passed through the band over each tube,

and thence through the tubes. The tubes thus 30
placed together form thimbles, which slip
readily over the barrels of the holders.

The manner of using the device is as fol-
lows: The two holders are placed in the thim-
bles and secured by the set-screws. The pens 35
c c are inserted in the holders, single or double
nibbed pens, or one of each kind, being used,
as in the drawings. If the pens are of different
lengths, their nibs can be brought to the same
plane by a proper adjustment of the holders 40
in the thimbles. In this way the two holders
and the pens are firmly connected together and
to the staff. In using them the two nibs are
placed upon the paper at the same time, and
thus several parallel lines can be drawn at the 45
same stroke.

Having thus described my invention, I claim
as new and desire to secure by Letters Pat-
ent—

As an improvement in pen-holders, the tubes 50
C C, connected together by solder and the
band a, and provided with set-screws b b, in
combination with holders B B' and staff A,
substantially as described.

DANIEL HEPP.
